CLAIM

The ornamental design for cubed bead with sloped hole, as shown and described.

DESCRIPTION

FIG. 1 is a perspective view of the cubed bead with sloped hole.

FIG. 2 is a bottom view of the cubed bead with sloped hole.

FIG. 3 is a top view of the cubed bead with sloped hole.

FIG. 4 is a representative side view of the cube; the front-,

back-, right-, and left-sides of the cubed bead with sloped

hole are identical; and,

FIG. 5 is a cross-sectional, side view of the cubed bead with

sloped hole.
